UNITED STATES PATENT OFFICE

LESTER S. GUNDERMAN, OF PITTSBURGH, PENNSYLVANIA

SAFETY DEVICE FOR CLOTHES WRINGERS

Application filed November 2, 1929. Serial No. 404,254.

This invention relates to a safety device for clothes wringers and particularly to a feeding means therefor, whereby articles of clothing can be brought to the bite of the press rolls without danger to the operator and without any necessity of the operator bringing his hands into contact with the rolls.

The invention has for one of its principal objects a feeding device having a movable feed plate and a guide plate loosely mounted on a bell crank in such a position that they will raise clothes to the bite of the press rolls.

Another object of this invention is to provide a device of this kind wherein the inner longitudinal edge of the guard is resiliently held towards the wringer rolls, preventing clothing from being torn if it should become wrapped around the rolls.

A further important object is to provide a device of this kind wherein the upper edge of the feed plate will resiliently hold the clothes against the upper roll over which it is drawn into the pass between the rolls and which can yield to the thickness of the material being passed through the wringer.

A further object is to provide a combination guide and feed plate to raise clothes to the bite of the press rolls.

A still further object is to provide a simple compact and efficient device which can be cheaply manufactured.

Figure 1 is a front view of a wringer and my invention thereon, having a section broken away showing the mounting of the parts.

Figure 2 is an end view of the wringer and the device mounted on both front and back of the wringer in relation thereto.

Figure 3 is a part sectional view on line A—A, Figure 2, and for convenience I have shown a feeder mounted on only one side of the wringer.

Figure 4 is an enlarged section taken on line B—B in Figure 1 and shows the feed plate in an inoperative position and the guide plate in a position to guide clothing away from the press rolls.

Figure 5 is an enlarged section taken on line B—B in Figure 1 and shows the feed plate

and guide plate in an effective position as when feeding clothes to the press rolls.

In a more particular description of the parts, 7 designates the usual metal wringer frame having two uprights in which are mounted the two wringer rolls 8 and 9 which are driven in a well known manner.

Thus far the elements referred to embody well known parts of a power driven wringer.

My improved construction of a feeding device comprises bracket members 10a and 10b which are mounted on the wringer frame by screws 11, or such suitable fastening. The lower portion of the bracket members 10a and 10b have yoke bearings 12 in which is loosely mounted a bell crank 13, the outward extended ends 14 thereof being used for operating handles.

Extending across between the brackets 10a is a guide plate 15 having its inner edge near the ends thereof loosely mounted on the bell crank at 16.

The plate 15 slopes downwardly towards the front and the front edge 17 thereof is bent downwardly on a radius from the bearing 16. Extending across the distance between the two brackets 10a is a curved vertically extended feed plate 18, the lower edge 19 thereof being loosely mounted on the center of the bell crank 13. The curvature of the feed plate conforms substantially to the radius of the distance between the center of the bell crank bearing and the upper edge of the feed plate 18. The upper longitudinal edge of the feed plate 18 normally lies in front of the guide plate 15, and is held in position by retaining plates 20 mounted on the guide 15, being means for guiding the feed plate 18 inward toward the press rolls.

The upward extended ends 21 of the guide plate 15 is bent at right angles at 22 to engage with the reversely right angle bends 24 on projection 23 of the bracket member 10a.

When the guide plate 15 is in its normal position the angle bends 22 rest on the angle bends 24.

In order to resiliently urge the guide 15 and the bell crank 13 inwardly toward the lower press roll flat springs 25 are provided, one end of each being secured to bracket 10a and 10b,

the other ends of the springs bearing against the bell crank 13 at 26, resiliently holding the bell crank at its innermost position in link members 12. The feed plate is raised from a 5 position shown in Figure 4 to a position shown in Figure 5; the forwardmost edge of the feed plate 18 can yield downwardly when it comes in contact with the upper roll. If clothing is being fed through the wringer, the 10 upper edge of the plate 18 may be depressed an amount equal to the thickness of the clothes so that the clothes will be resiliently held against the lower surface of the upper roll and drawn by the movement of the roll into 15 the pass between the two rolls.

The bell crank 13 and the guide 15 are held in their innermost position in yoke bearings 12 by springs 25 and if clothes being fed through the wringer should become wrapped 20 around the rolls the guide 15 may be moved outward thereby the amount equal to the thickness of the clothes so that the clothes will not become injured thereby.

When the operating handles 14 are raised 25 from a position shown in Figure 4 to the position shown in Figure 5 the feed plate 18 is rocked through a corresponding arc. The rocking of the feed plate 18 also rocks the guide 15 when the lower edge 19 of the feed 30 plate comes in contact with the edge 17 of the guide 15. When the feed plate 18 is in its innermost position the angle bend 22 abuts the wringer frame 7 thereby preventing the feed plate 18 from being drawn into the rolls.

35 When the feed plate and guide are in a retractive position shown in Figure 4 a portion of the clothes are placed on the guide. The handles 14 are raised and the forward edge of the feed plate 18 carries the clothes so positioned against the lower surface of the upper roll. The clothes thus brought into contact with the lower surface of the upper roll are drawn into the pass between the rolls. When 40 the clothes are not bunched or when the material is relatively thin the plate 18 will yield only slightly, but when the clothes are thick or are considerably bunched the plate 18 can be pressed forwardly against the springs 25 to an extent sufficient to permit such clothes 45 to be dragged or pulled through the wringer.

50 In the accompanying drawings and description I have illustrated and described a preferred embodiment of my invention, but it will be understood that the invention may 55 be otherwise embodied and various changes and modifications may be in the structure thereof within the contemplation of my invention and under the scope of the following claims.

60 I claim:

1. In an attachment for a clothes wringer frame having press rolls journaled on the frame, a bell crank journaled in the said frame, a feed plate extending transversely 65 across the wringer and loosely hinged to said

bell crank, a guide plate extending transversely across the wringer and hinged to said bell crank and being adapted to guide clothes to the wringer and pivoted to swing upward upon swinging of the feed plate to carry 70 clothes to the press rolls.

2. In an attachment for a clothes wringer frame having press rolls, of a feeding device comprising a feed plate extending transversely across the wringer the lower edge 75 thereof loosely hinged to the center portion of a bell crank having journals in said wringer frame, of a guide plate extending transversely across the wringer having its inner ends loosely hinged on the said bell 80 crank and normally lying between the wringer rolls and the upper edge of said feed plate and being mounted to rock upward with the feed plate towards the press rolls.

3. A feeding device for clothes wringers 85 including a pair of brackets mounted thereon, a bell crank supported by said members, a guide plate having one edge loosely hinged to said bell crank, a feed plate having one edge loosely hinged to said bell crank and 90 movable in front of said guide plate toward and away from the rolls to which the device is applied.

4. A feeding device for clothes wringers comprising brackets thereon, a bell crank 95 loosely mounted thereon, a guide plate loosely supported on said bell crank, a feed plate guiding means on said guide plate for said feed plate, resilient elements operatively interposed between the brackets and the bell 100 crank for yieldingly permitting a slight relative movement between the feed plate and the rolls, said feed plate being adapted to normally lie in front of the guide plate.

5. A feeding device for clothes wringers 105 comprising brackets disposed at each side of the wringer frame, said brackets having slotted bearings therein which slots are directed away from the rolls to which the device is attached, a bell crank slidably engaged 110 in said bearings, a guide plate loosely hinged on said bell crank, said guide having the front edge thereof receding away from the rolls, a feed plate loosely hinged on the bell crank, resilient means interposed between the 115 brackets and the bell crank for yieldably permitting a slight relative movement between the guides and press rolls and operating means connected with the bell crank.

6. A feeding device for a wringer comprising 120 bracket members on each side of the wringer, said brackets having slotted guide bearings therein which are directed outwardly away from the rolls of the wringer to which the device is applied, a bell crank 125 mounted in said bearings, a guide plate having its ends mounted on the bell crank and its outer edge movable upwardly toward the wringer rolls, a feed plate with its upper edge in front of the said guide and the lower 130

5 edge thereof loosely mounted on said bell crank, means on said guide plate to direct the feed plate toward the wringer rolls, resilient means on the bracket resting over the bell crank for yieldably permitting a slight movement of the guide plate away from the press rolls, and operating means on said bell crank.

10 7. A feeding device for a wringer comprising bracket members on a wringer frame, said brackets having slotted bearings therein which are directed outwardly away from the rolls of the wringer to which the device is applied, a bell crank mounted in said bearings, a guide plate between said brackets connected with said bell crank, a feed plate connected with said bell crank and its upper longitudinal edge normally lying in front of said guide plate, means on guide plate to direct the feed plate in a circular path, springs on the brackets engaging said bell crank to yieldably permit a slight movement of said plates away from the wringer rolls and operating means on said bell crank.
